UNITED STATES PATENT OFFICE.

ARTHUR RHODES AND CLIFFORD RHODES, OF KEIGHLEY, ENGLAND.

DRAWING ROLLERS OF SPINNING, DOUBLING, TWISTING AND LIKE MACHINES.

Application filed August 16, 1927, Serial No. 213,304, and in Great Britain August 17, 1926.

In the spinning of fibrous substances, especially those of long fibers as wool, mohair and the like, the drawing rollers of the spinning, doubling, twisting and like machines are to be adjusted at varied distances apart from each other to meet the requirements of longer or shorter fibers. In order to carry such fibers during the attenuation of the threads, rotary rollers known as "carrier rollers" are mounted between the back pair of drawing rollers and front pair of drawing rollers.

In order to transmit rotary motion to the carrier rollers, gear trains have usually been employed, capable of adjustment to the different positions which these rollers must occupy. These gear trains and the protecting guards necessary therefor, usually occupy so much space above the rollers as to obstruct the operator's view of the machine parts adjacent to the gear train.

The object of the present invention is to provide a mechanism which will transmit the desired rotary motion to the carrier rollers and permit their adjustment as occasion may demand without encountering the objection hereinbefore given. Briefly stated, this is accomplished by employing as the transmission mechanism, endless flexible gear or sprocket driving members, such as an endless flexible rack or a chain, so arranged and supported that the desired rotary motion is transmitted to the rollers.

With these and other objects in view, our invention may best be understood by the following description, in conjunction with the accompanying drawings, wherein

Fig. 1 is a left side elevation of the upper part of a machine embodying the present invention, with the usual driving gears shown diagrammatically or by broken lines so as to show their connection to the shaft of the front drawing roller.

Fig. 2 is a plan view of the parts shown in Fig. 1.

Fig. 3 and Fig. 4 are views similar to Figures 1 and 2, respectively, but taken looking at the right hand side of the machine.

Fig. 5 and Fig. 6 are detail views of the transmission mechanism, with some parts broken away for clearness.

Fig. 7 and Fig. 8 are views similar to Figures 5 and 6, respectively, but showing a modified form of transmission mechanism.

Fig. 9 and Fig. 10 are elevation and plan

views, respectively, of parts shown in Figures 5 and 6, drawn to a larger scale.

Referring to the drawings, A indicates a side frame of the usual spinning and twisting machine, B the shaft of the front drawing rollers, and C the shaft of the back drawing rollers. In accordance with the present invention, the usual gear train, which comprises gears of comparatively large diameter to drive the carrier rollers from the back roller, is dispensed with. In place of this train of gears, we employ an endless flexible rack 2, which as best shown in Fig. 5, is made up of comparatively short sections linked together by pivots P and having teeth 2^a extending from one edge thereof. These teeth conform in shape with the teeth of the usual gear-racks, so that they may be meshed with the teeth of the usual gears. One of these endless racks is provided at each side of the machine and is arranged to drive one or more carrier rollers.

One of the endless racks (see Figures 1 and 2) is driven by a gear 3^a of the shaft C of the back roll from the shaft B of the front roll, which derives its motion from a suitable source of power (not shown). Motion is transmitted to the back roll by a gear train consisting of a gear 8 fixed to the shaft B and meshing with a gear 9 on one end of a shaft 9^a to the other end of which is fixed a gear 10 meshing with a gear 11 on the shaft C. The rack 2 meshes with a gear 3^b fixed on the shaft 7 of one of the carrier rolls.

The endless rack 20 on the other side of the machine (see Figures 3 and 4) is arranged to drive the other carrier rollers. To this end, a gear 3 is fixed to the shaft C and meshes with a gear a' fixed to a stud shaft a² mounted in an adjustable bearing bracket a² fixed to the frame A. A gear a² fixed to the shaft a⁴ meshes with a gear a mounted on a stud shaft a⁵ carried by the bracket a³. The gear a meshes with the rack 20, which in turn meshes with gears 3^b and 3^c, respectively fixed on the shafts 30 and 40 of the other carrier rolls.

The endless flexible racks are guided in fixed paths so as to mesh properly with the various gears as hereinbefore described, and are so mounted as to be adjusted in accordance with the size of the gears 3 and 3^a on opposite ends of the shaft. To this end, as best shown in Figures 5 and 6, the rack 2 is

slidably engaged within grooves formed at the upper and lower ends of a plate support 4. The inner face of the rack is slidable on the flat bottom faces of the grooves and the side faces of the rack slide against the inner faces of the side walls 4, 4^a of the grooves, so that lateral displacement of the rack is avoided. The plate is recessed at its ends for the reception of guide rolls 2^a and 2^b, about which the racks pass and which turn freely on supporting studs W^a and W^b fixed to the plate 4. As shown in Figures 1 and 2, the support 4 and rack 2 are supported as a unit, at the back roll, by an adjustable bracket 6, and at the front end by a bracket 16 fixed to the frame A of the machine. When the gear 3^d is changed from one size to another, as conditions or the character of the work being operated upon may require, the rack 2 may be kept in mesh with the gear 3^d at the same time adjusted to mesh with the new-sized gear 3^a. The rack 20, together with its support, on the side of the machine shown in Figures 3 and 4, is supported at the back roll and at the front end of the machine by brackets 160 fixed to the frame A and similar to the bracket 16, no adjustment of this rack being needed, even when the gear 20 is changed from one size to another to meet varying conditions, or the character of the work being operated upon. The bracket a^a may be adjusted to effect proper meshing in the gear train 3, a¹, a² and a.

In lieu of using a flexible endless rack as the transmission mechanism, we may use an endless, flexible, gear-driving mechanism in the form of a chain C made up of spaced side links 2^d pivotally secured to rollers 2^c. The chain may be guided and supported in a manner similar to the endless rack to drive sprocket wheels 3^c and 3^w fixed to the shafts of the rollers, rather than the usual gears.

Having thus described certain embodiments of this invention, it is evident to those skilled in the art that various changes and modifications might be made therein without departing from the spirit or scope of the invention as defined by the appended claims.

What we claim is:

1. A machine of the class described, comprising in combination front, back, and a plurality of intermediate drawing rollers, geared shafts associated with each of said rollers, and an endless flexible rack driven by said back roller shaft, said rack meshing with the gears of certain of said intermediate roller shafts.
2. A machine of the class described, comprising in combination front, back, and a plurality of intermediate drawing rolls, geared shafts associated with each of said

rollers, an endless flexible rack driven by said back roller shaft, and a member for supporting and guiding said rack, comprising grooves in which said rack slidably engages and rolls about which said rack passes, said rack meshing with the gears of certain of said intermediate roller shafts.

3. A machine of the class described, comprising in combination front, back, and a plurality of intermediate drawing rollers, geared shafts associated with each of said rollers, and an endless flexible rack on each side of the machine driven from said back roller shaft, one of said racks meshing directly with the gear on said back roller shaft and the other of said racks meshing through a train of gears with a gear on said back roller shaft, said racks meshing with the gears of the intermediate roller shafts.

4. A machine of the class described, comprising in combination front, back, and a plurality of intermediate drawing rollers, geared shafts associated with each of said rollers, an endless flexible rack on each side of the machine driven from said back roller shaft, a member for supporting and guiding each rack, one of said racks meshing directly with a gear on said back roller shaft and a gear on one of said intermediate roller shafts and the other of said racks meshing through a train of gears with a gear on said back roller shaft and directly with the gears on the other intermediate roller shafts, and means for adjusting the supporting member of said first-mentioned rack when the gear on the back roller shaft with which it directly meshes is changed.

5. A machine of the class described, comprising in combination front, back, and a plurality of intermediate drawing rollers, geared shafts associated with each of said rollers, and a gear transmission mechanism from said front roller shaft to said back roller shaft, an endless flexible rack on each side of the machine driven from said back roller shaft and comprising pivotally linked sections having gear teeth, a member for supporting and guiding each rack, one of said racks meshing directly with a gear on said back roller shaft, and a gear on one of said intermediate roller shafts and the other of said racks meshing through a train of gears with a gear on said back roller shaft and directly with the gears of the other intermediate roller shafts, means for adjusting said train of gears when the gear of said train on the back roller shaft is changed, and means for adjusting the supporting member of said first-mentioned rack when the gear on the back roller shaft with which it directly meshes is changed.
